UNITED STATES PATENT OFFICE.

HARRY M. KORETZKY, OF NEW YORK, N. Y.

PORTABLE ELECTRIC LAMP.

Application filed May 31, 1923. Serial No. 642,544.

The present invention relates to an improvement in portable flashlights, and more particularly to that type of flashlights which is adapted to vary the focusing of the light 5 in order to concentrate it at will upon objects at various distances from the user. One principal object of the invention is to provide a simple, easily constructed and convenient form of adjustable and removable 10 support for the incandescent lamp, whereby a reliable contact may always be effected for connecting the lamp with the battery and switch.

Another principal object of the invention 15 is the provision of a simple and inexpensive mounting for the lamp which greatly facilitates replacements in case of breakage of the lamp.

The invention is illustrated in a preferred 20 form in the accompanying drawings, wherein Figure 1 is a side elevation of the complete device, Figures 2, 2^a and 2^b show the parts at the forward end of the device, partly in section, and partly in side elevation, 25 the same being shown separated, Figure 3 is a plan view of the removable lamp support, Figures 4, 4^a and 4^b show, partly in section and partly in side elevation, the lamp and lamp support with the intermediate false 30 socket, all shown separated. Figure 5 is a partial sectional view of the lamp support on the line x—x in Figure 3, and Figure 6 is a sectional view of a modified form of 35 false socket shown in place.

The flashlight as a whole comprises an exterior casing 10 preferably cylindrical in form, which may be made either of metal (as in the form shown) or of fiber or other 40 insulating material; as is well understood in this art. In either case the battery 11 is introduced in the usual manner at the rear end, being held in place by the usual screw cap 12. Where the casing 10 is made of metal, contact with the zinc terminal of the 45 battery is accomplished through an internal metal spring 13 (insulated from the casing as shown) thence through the switch 14 to the casing 10 and cap 12. This last usually 50 carries an interior spiral spring, shown in dotted lines, which makes direct contact with the zinc of the battery at the rear end. These details are all well known in the art.

Of course, where a casing 10 of insulating 55 material is used, the method of making connections may be varied in any manner well known in the art in this connection.

At 15 is shown a front cap which screws onto the forward end of the casing. This cap is preferably furnished with a plane glass 16, and carries a suitably shaped reflector 17 having a central opening at 18, through which the lamp 19 protrudes when the whole is assembled. By screwing the cap 15 in or out, the relative positions of the lamp and reflector may be varied to change 60 the focal distance.

The present invention relates especially to the mounting of the lamp 19 and to means which support the mounting and accomplish effective connection between the lamp on the 70 one hand and the battery on the other hand.

The improved connecting support comprises two metal members attached to an intermediate insulating disc which prevents 75 electrical connection between these members—while serving to connect them mechanically.

The outer metal member consists of a disc 20 having an upturned screw-threaded peripheral flange 21, so threaded as to adapt 80 it to be screwed into the threaded end 22 of the casing 10. The disc 20 has a central aperture 23.

The inner metallic member of the connecting support consists of a disc 24 whose 85 central portion is formed into a threaded socket 25 which projects upward through the opening 23 in the disc 20, leaving an annular space between the socket 25 and disc 20, as shown.

In order to fasten the two members 20 and 24 to the intermediate insulating disc 26, the following preferred construction is adopted.

The inner member 24 is fastened to the 95 insulating disc 26 by two diametrically placed hollow metal rivets 27, and, in order to avoid establishing electric connection between the members 20 and 24 through these rivets, openings 28 are made in the disc 20 100 around each rivet which are large enough to avoid contact therewith. Figure 4^b is a sectional view through the rivets 27, showing this construction.

In order to establish a similar mechanical 105 and non-electrical connection between the outer member 20 and the disc 26, similar rivets 29 are used, and the inner ends of these rivets are countersunk in the disc 26 (see Figure 5) so that they do not touch 110 the inner member 24.

At 30 are shown two raised finger pieces

which may have any suitable form, which are preferably struck up from the disc 20, and serve to facilitate the turning of the connecting support when it is being screwed 5 into or out of the threaded end 22 of the casing.

In the ordinary use of flashlights of this general character it frequently happens that the lamp 19 becomes broken, leaving not 10 enough of the lamp to be seized by the user, so that the whole device has to go to the factory or to a workshop to have the lamp removed. This is a wide-spread cause of annoyance and dissatisfaction.

15 In order to remedy the trouble, one feature of the present invention provides a "false socket" or intermediate threaded nipple 31 into which the lamp 19 may be screwed. This nipple is then screwed down 20 into the socket 25. The nipple 31 is made slightly tapering, so that it will only screw inward a certain definite distance (see Figure 2^a). If, now, the lamp 19 be broken, the nipple 31 is unscrewed together with 25 the lamp, and both may be thrown away. As the nipples 31 are very inexpensive and can be supplied as additional parts, the replacement of new lamps in case of breakage becomes a very simple matter, involving 30 practically no loss of time.

It is, of course, not essential that the false socket or nipple should be inserted from the front of the connecting support. In Figure 6 is shown a modification, in which the nipple 35 is inserted from the under side. In this form the lamp is screwed into place after the nipple is inserted. As shown in Figure 6, the nipple is composed of a threaded metallic shell 33 in the bottom of which is the metal 40 plug 34, supported by the insulation 35. This plug provides electrical connection between the central terminal of the lamp 19, which touches its upper end, and the carbon

terminal 32 of the battery, which touches its lower end. 45

In assembling the flashlight, the lamp 19 and nipple 31 are screwed into place (see Figure 2^a) and the connecting support is then screwed down, by the assistance of the finger holds 30, within the threaded neck 22, until the disc 24 compresses the bent end of the contact spring 13, and the tip of the nipple 31 touches the carbon terminal of the battery at 32. 50

When the switch 14 is closed in the usual 55 manner, circuit is established from the battery terminal 32, through the lamp 19, nipple 31, socket 25, disc 24, spring 13, switch 14, casing 10, cap 12, and to the zinc terminal of the battery. 60

Various changes may be made in different parts of the device as shown without departing from the scope of the invention, which is not limited to the details herein shown and described. 65

What is claimed is:—

1. In a portable flashlight, an external casing having a threaded neck, a connecting support having a socket for a lamp and adapted to be screwed into said neck, said connecting support comprising an exterior member having finger holds on its surface to facilitate manipulation of the connecting support. 70

2. In a portable flashlight, a connecting support for the lamp proper having a central threaded portion, in combination with a false socket adapted to be screwed into said threaded portion from below and comprising a threaded metallic shell, an insulating base and a metal plug passing through said base and adapted to connect one bulb terminal with the battery. 75 80

In testimony whereof I have hereto set my hand on this 25 day of May, 1923.

HARRY M. KORETZKY.
